(57) **CLAIM**

The ornamental design for a roofing apparatus, as shown and described.

DESCRIPTION

FIG. 1 is a perspective view of a roofing apparatus, showing the new design;

FIG. 2 is a front elevational view of the roofing apparatus; and

FIG. 3 is a top plan view of the roofing apparatus; and,

FIG. 4 is a rear elevational view of the roofing apparatus; and,
FIG. 5 is a side elevational view of the roofing apparatus. The broken line showing of the remainder of the roofing apparatus is for illustrative purposes only and forms no part of the claimed design.
